UNITED STATES PATENT OFFICE.

MELVIN J. PARKER, OF QUIMBY, IOWA.

JACKSCREW EXTENSION ATTACHMENT.

Application filed October 28, 1920. Serial No. 420,125.

To all whom it may concern:

Be it known that I, MELVIN J. PARKER, a citizen of the United States of America, and resident of Quimby, Cherokee County, Iowa, have invented a new and useful Jackscrew Extension Attachment, of which the following is a specification.

The object of this invention is to provide an improved extension for jack-screws which may be readily and quickly applied thereto to increase the capacity of the jack-screw.

A further object of this invention is to provide improved means for removably and replaceably attaching an extension device to a jack-screw.

With these and other objects in view, my invention consists in the construction, arrangement and combination of elements hereinafter set forth, pointed out in my claims and illustrated by the accompanying drawing, in which—

Figures 1 and 2 are elevations, at right angles to each other, illustrating a jack-screw with one of my improved extension attachments applied thereto. Figure 3 is an elevation, partly in section, one member of the extension attachment being removed and the hinge and latching devices being omitted. Figure 4 is a cross-section on the line 4—4 of Figure 3.

In the construction of the device as shown the numeral 10 designates the base of a jack-screw, provided with a threaded vertical bore 11 receiving a screw 12 having a head 13 swiveled to its upper end. Immediately below the head 13 a collar 14 is fixed to the screw and is provided with one or more diametrical holes 15 to receive a bar or rod (not shown) for rotating the screw in a common manner.

The extension attachment is in the nature of a jacket or sleeve formed of two mating members 16, 17 adapted to be mounted on and supplement the base 10. The members 16, 17 when closed together preferably are of the same diameter as the upper portion of the base and are together formed with a vertical threaded bore 18 corresponding to and alining with the bore 11 thereof, when the attachment is in place. The base 10 preferably is formed at its upper end with a portion 19 reduced in diameter, producing a square peripheral shoulder 20; and the members 16, 17 of the attachment are formed at their lower ends with a cylindrical recess concentric with the bore 18 and fitted to

the reduced portion 19, so that the lower ends of said members, outside of said recess, may engage and rest on the shoulder 20. In this manner the members of the attachment may be secured to and supported by the base and form an extension thereof. As shown, the member 16 is formed with a pair of spaced, vertically alining apertured ears 21 registering with similar ears 22 on the member 17, through which ears passes a hinge bolt or pintle rod 23, whereby the extension members are hingedly secured together. Means is provided for latching the members 16, 17 together at their opposite margins, as follows: Spaced ears 24 are formed on and project from the member 17 and are formed with horizontal apertures 25, through which are loosely mounted bolts 26. On the member 16 are formed forked ears 27, having their forks in transverse alinement with the apertures of the ears 24 and adapted to receive the bolts 26 at times. Pivoted by pins 31 to the ends of the bolts 26 are cam latching levers 28, decentered on said pins and having cam faces adapted to engage the outer surfaces of the forked ears 27, whereby the free margins of the hinged extension members 16, 17 may be drawn and held closely together in the position shown relative to the base, the lower end portions of said members 16, 17 clamping and frictionally engaging the cylindrical portion 19 of the base.

In use the extension attachment may be applied and secured to the base as shown to the end of increasing the capacity of the jack, it being possible for the screw 12 to move upwardly into and be supported wholly by said attachment after leaving the bore of the base. The upper end of the extension members preferably are formed with a reduced portion 29 forming a shoulder 30, similar to and corresponding with the reduced portion and shoulder of the base, so that other extension members, identical with 16, 17, may be added thereto to further increase the capacity of the device.

The members are readily and quickly removed and replaced; and the extension is formed in two parts hinged together as shown and described for convenience in such operation, and so that they may be added without removal of the screw from the base. It is obvious that the extension attachment might be formed of a solid cylindrical bored

- member, but with the construction shown the attachment may be added even after the jack proper is in place and in supporting position relative to a load; and that the several extensions are frictionally engaged with each other or with the base to prevent rotation of an extension by the screw, thus avoiding the use of set screws to connect them.
- 10 It should be noted that when the extension is in place it forms a continuation of the base member of substantially the same diameter as and merging into said base; and that no projections or enlargements are formed on the base which might render it unfit or inconvenient for use independently of the attachment.
- 15

I claim as my invention—

In a jack-screw having a base and a screw threaded therein, said base being formed with a reduced cylindrical upper end portion, an extension attachment formed of substantially like semi-cylindrical members, said members being formed with relatively movable arcuate portions adapted to embrace said reduced portion of the base, said members also being formed with reduced arcuate portions adapted conjunctively to be embraced by superposed duplicate members.

Signed at Quimby, in the county of Cherokee and State of Iowa, this 24th day of September, 1920.

MELVIN J. PARKER.
